L. G. Smith Inventor
By his Attorney J. O. Fowler

UNITED STATES PATENT OFFICE.

LINCOLN G. SMITH, OF FLEMINGTON, NEW JERSEY.

DESIGN FOR A MONEY-RECEPTACLE.

SPECIFICATION forming part of Design No. 22,323, dated April 4, 1893.

Application filed January 6, 1893. Serial No. 457,577. Term of patent 3½ years.

To all whom it may concern:

Be it known that I, LINCOLN G. SMITH, a citizen of the United States, and a resident of Flemington, in the county of Hunterdon and State of New Jersey, certify that I have invented a certain new and original Design for a Money-Receptacle, of which the following is a specification, reference being had to the accompanying drawing, showing a front elevation thereof.

The leading feature of my design for a money receptacle is a representation of a globe or sphere A, provided with an annular rim A' forming the base or foot thereof and a central bead B'. One side of the sphere is ornamented by a representation of a locomotive and railroad track B' placed thereon. A

curved panel within parallel lines indicate reserved space for any suitable words, dates, or legends.

What I claim as my invention, and desire to secure by Letters Patent, is—

The design for a money receptacle substantially as shown and described.

In testimony of the foregoing specification I do hereby sign the same, in the city of Flemington, county of Hunterdon, and State of New Jersey, this 21st day of December, A. D., 1892.

LINCOLN G. SMITH.
